UNITED STATES PATENT OFFICE.

WILLIAM ZOERB, OF DEDHAM, MASSACHUSETTS, ASSIGNOR, BY MESNE ASSIGNMENTS, TO ELIZABETH ZOERB, OF SAME PLACE.

DESIGN FOR AN EYEGLASS-CASE.

SPECIFICATION forming part of Design No. 30,307, dated March 7, 1899.

Application filed January 16, 1899. Serial No. 702,363. Term of patent 14 years.

To all whom it may concern:

Be it known that I, WILLIAM ZOERB, a citizen of the United States, residing at Dedham, in the county of Norfolk and State of Massachusetts, have invented and produced a new and original Design for an Eyeglass-Case, of which the following is a specification, reference being had to the accompanying drawings, forming a part thereof.

10 Figure 1 shows a plan view of an eyeglass-case, illustrating my new design. Fig. 2 is a front edge view of the same, and Fig. 3 a right-hand end view of the same.

15 The leading feature of my design consists, essentially, in the lid of the eyeglass-case, made narrower than the body of the case for a portion of its length and made as wide as the body of the case for a portion of its length, the narrow part of said lid exposing 20 the front edge of the body of the case and the wide part concealing the body of the case.

The oblong case a has a lid a' hinged to it along its rear edge. The lid a' has a cut-away portion a^2 , which reduces its width and which exposes a portion of the front edge of the body of the case a , and said lid a' has a projecting lip a^3 , which extends to the front edge of the body of the case, thereby concealing a portion of the body of the case. 25

I claim—

30 The design for an eyeglass-case herein shown and described.

In testimony whereof I have signed my name to this specification in the presence of two subscribing witnesses.

WILLIAM ZOERB.
